Kathryn L Allison INVENTOR.

UNITED STATES PATENT OFFICE.

KATHRYN L. ALLISON, OF LOS ANGELES, CALIFORNIA.

COMBINATION VANITY CASE.

Application filed August 16, 1926. Serial No. 129,360.

This invention relates to improvements in toilet cases and more particularly to a combination vanity compact and coin case.

One of the objects of the present invention is to provide a simple, efficient and inexpensive device of this character wherein space is suitably appropriated in a casing for a lipstick, eyelash pencil, rouge, powder, a powder compact and whereby means is provided for containing coins of various denominations.

Another object of my invention is to provide a casing designed to be attached to the wrist of the user's arm and instantly affording the user access to various toilet or face preparations such as face powder, a compact, rouge, a lipstick, and the like.

A still further object of my invention is to provide a convenient compact case which is provided with a plurality of compartments, the central compartment of which is the narrowest so that a container holding a lipstick and eyebrow pencil may snugly fit the central narrow compartment, and wherein face powder may fill another compartment with a compact overlying the same, and rouge may occupy another compartment.

A further object of my invention is to provide improved means for containing coins of various denominations and also designed to have a strap to secure the device around the wrist of the user. To this end I have provided a compact wherein various pockets are provided to hold various toilet accessories and outside of which are carried two coin cases arranged on opposite sides of the casing thus allowing coins to be carried about with the vanity casing, and enabling the user to always have about her toilet preparations together with the means of applying the same.

In carrying out the details of my invention I contemplate providing a cylinder in two parts, one frictionally fitted onto the other and so disposed that there may be lodged therein a combination lipstick and pencil formed in one continuous length held together by means of a central collar. This cylinder is designed to be deposited in a central relatively narrow compartment formed in the vanity toilet box.

With the above and other objects in view my invention consists in the combination, arrangement and details of construction dis-

closed in the drawing and specification, and then more particularly pointed out in the appended claims.

In the drawings, wherein similar reference characters designate similar parts throughout the respective views,

Figure 1 is a top plan view of my invention, partly in section, with the casing cover open,

Figure 2 is a longitudinal section thru my invention taken on the bar forming the transverse base line thereof, showing the lid in closed position,

Figure 3 is a side elevation of my invention,

Figure 4 is a transverse view of my invention showing all the lids or covers in open position, and

Figure 5 is a top plan view of my invention showing the wrist engaging strap forming part thereof.

In the drawings, which are merely illustrative of my invention 10 designates the lid or cover associated with a vanity casing 11; casing and cover can be of any desired shape but I prefer to form the casing and cover as shown in Figure 1 where it will be seen that casing 11 is formed V-shaped at opposite ends as at 12, 13, the lid being correspondingly shaped as at 12^a, 13^a. The lid and casing will preferably be of uniform depth, and will be movably connected by the conventional hinges 21. A suitable mirror 14 is disposed against the back wall of the lid 10. A bar is disposed flush with the bottom of the toilet casing 11 and its terminals assume the form of two arms 15 and 16 respectively disposed transversely of the longitudinal axis of this toilet casing. The undersides of these arms are designated B and C. Formed integrally upon the ends of arms 15 and 16 respectively are coin casings 17^a and 18^a having hinged thereupon lids 17 and 18, these coin cases or boxes being of varying diameters to hold coins of various denominations. Any desirable form of clip 23 is designed to frictionally lock the lid 17 or 18 upon their respective coin cases. It will be seen from Figure 4 that lid 17 opens out away from the toilet casing and towards the adjacent end of arm 16, while lid 18 similarly opens out upon its coin case in the direction of the adjacent end of arm 15. The lid 10 is also designed to have a spring clip

100
105

associated therewith to lock it firmly and securely upon the toilet case 11.

I design to form a plurality of compartments or pockets within the casing 11, preferably three being provided, such that the central compartment is relatively narrow, while the endmost compartments are widest. Lodged in one end compartment will be rouge 26, and in the other end face powder 27, and 10 overlying the face powder is a compact or powder puff 28 having the usual hand hold or strap 29. The compact 28 snugly fits its own compartment, as does the rouge 26, and has a terminal V-shaped edge coming to a 15 point, for the purpose of, being used about the nose and lip of the user. This V-shaped edge of the compact will, without waste of powder, reach parts of the face where it is especially desirable to apply a uniform film 20 of powder without allowing the compact to touch adjacent parts of the face.

Designed to lodge itself within the central relatively narrow compartment is a receptacle, container or cylinder consisting of two 25 tubular members 33 and 34, one frictionally engaging the other in telescopic relation and each contact endwise with the other. A metal band engages the central portion of a continuous length of a stick, one half of which 30 is a lipstick 30 while the other is an eye-lash pencil 31, the embracing band being designated 32. This receptacle thus snugly secures and in a sanitary manner protects the eyelash pencil and the lipstick. In order to 35 assure that the lid 10 will move to an inclined position as it is opened and thus afford clearance for the coin case lid 17 to swing in its arc to open or closed position relatively to its coin case 17^a; I provide a lug 24 upon the arm 40 C upon which the lid 10 rests when in open position, as is shown in Figure 4.

At the end of arm 16 is formed a ring or loop 38 to which is attached one end of a flexible strap 37, while the other end of this 45 strap, after it is designed to embrace the wrist of a user is designed to have its terminal hook 36 engaged with the loop or ring 35 secured to the end of arm 15.

In operation the lady desiring to use my 50 invention will remove any of the toilet ar-

ticles contained in the casing 11, and may remove the powder compact 28 with powder thereupon and use the mirror 14 to advantage in applying, as this mirror is always available.

The strap 37 will be applied around the wrist of the user to secure the device in position upon the user's arm, after which the end of the strap will be hooked onto the loop 35 in this manner securing the device in position. By opening the lid 10 the casing is rendered accessible instantly. Definite places are thus assigned to the different toilet preparations and appliances. I do not mean to limit myself to the exact details of construction shown but mean to claim all variations coming within the purview of the appended claims.

What I desire to claim and secure by Letters Patent is:—

1. A compact formed with a V-shaped terminal.

2. A compact formed with a portion having opposing rightangular corners and another portion being V-shaped.

3. A compact formed with a rectangular terminal and with an axially disposed V-shaped terminal arranged opposite to said rectangular terminal.

4. As a new article of manufacture an eyelash pencil, a lipstick having their ends removably coupled by a common ring, and a pair of caps of uniform diameter held with a pressed fit against said ring with their edges contacting.

5. A device as described consisting of a pair of similarly shaped and sized trays hinged together to provide a case, a mirror mounted in one of said trays, a flange projecting beyond the bottom of the tray other than the mirror-carrying tray, and a lug formed upon said flange and serving to support said mirror-carrying tray when the latter is disposed in vertical position, to dispose said mirror vertically.

In witness whereof she has hereunto set her hand this twenty-eighth day of July, 1926.

KATHRYN L. ALLISON.
